ENGINEERS' PATENT PREPARATION KIT
Francis D. Brewer, 47 Mokema Ave., Waltham, Mass.
Filed Mar. 31, 1960. Ser. No. 18,919
1 Claim. (Cl. 33—76)

This application is a continuation-in-part application of my copending application No. 645,652 filed March 12, 1957.

This invention relates to drafting methods and apparatus for facilitating and controlling the preparation of patent illustrations such as those which normally complement the specifications of applications for United States Letters Patent, which applications follow prescribed governmental rules and standards.

The main purpose of the invention described herein-after is to have a compact portable drafting apparatus accompanied by necessary engineering and drafting equipment that can be readily set up in close quarters for the preparation of sketches as well as preliminary and final patent illustrations.

The invention includes, among its characteristic features, novel methods and means to facilitate and accelerate the processes of applying ink, dye, stain, or fluid coloring to bristol board, drawing paper, graph sheets, sketch sheets or other flat surfaces serving as vehicles for reception of such design-delineating materials. All such features supplement those aspects of the invention that are covered generically in my co-pending application No. 645,652 filed March 12, 1957, of which the present application is a continuation-in-part.

Fluid materials used in design and pictorial drafting, and analogous operations, as, for example, the inking of patent drawings, require a certain amount of time to "dry," that is, to be transformed from the fluid to the permanently set or solid state. During this "drying" period there is danger of blotting or smearing of the ink or other delineating fluid, as by either accidental or intentional brushing thereof in the process of moving the hand or some drafting aid (T-square or template, for example) across the surface area containing the recently applied ink or other marking fluid.

Heretofore efforts to avoid such blotting or smearing have led to the practice of interrupting the drafting or other illustrating operation, after each stroke of the drafting process, to permit the lapse of a period of time sufficient for completion of the ink-drying cycle; otherwise the movement of the T-square, template, or other drafting aid across the recently inked surface would be likely to produce objectionable blotting or smearing. This practice caused a loss of time and a natural nervous disturbance to draftsmen in waiting for the ink to dry.

The present invention provides methods and means permitting continuous, uninterrupted application of ink or other marking fluid, and continual adjusting progression of drafting aids across the work area in a manner that avoids physical contact between such drafting aids, on the one hand, and the still fluid ink, on the other, thereby eliminating or substantially minimizing the danger of smearing or otherwise defacing the illustration or design as it develops, stroke by stroke. Use of the principles of the present invention allows continual working over wetted surfaces by bridging over said surfaces, in contra-distinction to the old method of having the instruments lay directly on the work sheet.

The invention further provides methods and apparatus for orienting the work-sheet to the illustrator, in place of the old method of orienting the draftsman to the drawing.

Another feature of the invention lies in its ready adaptability to incorporation into apparatus of a portable nature, particularly suitable for use on tables, light-boxes, classroom desks; on suitable stands locatable on floors of

2

rooms and laboratories; in cars during transit or standing idle; as well as in the open air production of maps and other similar sketches necessary to technical subjects.

These and other objects, advantages, and features of my invention will become apparent upon consideration of the following detailed description of several embodiments thereof, especially when taken in conjunction with the accompanying drawings, in which:

FIG. 1 shows a drafting board having a recessed area equipped with a mat or pad upon which the drafting paper may be placed and securely held, and also having an outer margin adapted to support a drafting appliance in vertically spaced relation to the work sheet when the latter is placed in position upon such pad, thus facilitating practice of the invention;

FIG. 2 is a sectional view along line 2—2 of FIG. 1;

FIG. 3 is an isometric view of a drawing board assembly embodying the features illustrated in FIGS. 1 and 2, along with additional features;

FIG. 4 is a cross-sectional view along line 4—4 of FIG. 3;

FIG. 5 is an isometric view illustrating a modified form of the invention wherein a removable tray forms part of the assembly;

FIG. 6 is a cross-sectional view on line 6—6 of FIG. 5;

FIG. 7 is a modified cross sectional view at 7—7 of FIG. 6 representing a third embodiment of the invention;

FIG. 8 is a cross sectional view of a fourth embodiment of the invention, illustrating one method of combining recess, blade and pedestals for pivotal flexibility;

FIG. 9 shows how the supporting member with adhesive pad affixed is usable independently of any upper component by using a blade having a center finger pedestal and two exterior supporting screw pedestals as a means to keep said blade laterally constant above the work sheet; and

FIG. 9a is an exploded view of a main element of the invention, namely, the work-gripping pad.

FIGS. 1 and 2 show a laminated drawing board 10 having a depressed recess 12 wherein a work-gripping pad 11 has been inserted and securely fastened to surface 14 of drawing board 10.

Work-gripping pad 11 consists of a standard 10" x 15" patent bristol board having printed side up when located in recess 12 of drawing board 10, said pad 11 being adapted to receive a work sheet 20 for graphic delineating purposes well known to the art of patent drawings. The surfaces of the pad 11 are treated with adhesive material, prepared in the following manner: Spread a layer of white rubber based paper cement 15, well known to the graphic art, to the underside of bristol board 13 and immediately apply a similar layer of said cement to surface 14 of drawing board 10 as illustrated in FIGS. 1 and 2; then press the two wetted surfaces just mentioned downwards until solidified at the bottom of recess 12 to produce a permanent adhesion 15 and making work holding pad 11 an integral part of the drawing board 10. Work-gripping surface 16 of pad 11 is then prepared by spreading three applications of said paper cement on the top surface of bristol board 13 allowing sufficient time for each layer of cement to set before adding the next application. This method will produce a tacky adhesive surface 16 which is ready to receive work sheet 20 in a manner permitting application and removal of said sheet 20 as desired without damage to either the work sheet 20 or the adhesive surface 16 during the preparation of a patent drawing. Drawing board 10 comprises a base 10' of wood, as for example, a piece of marine plywood $\frac{1}{4}$ " thick x 12" wide x 20" long, and a rectilinear frame element 10" made of $\frac{1}{8}$ " thick plywood bonded or fastened by brads or screws to base 10'. Recess 12, having sub-recesses 18, is cut out to snug-fit around a standard

70

10" x 15" rectilinear patent bristol board prior to attaching frame 10" to base 10'. Work-gripping pad 11 is then prepared and cemented in place as previously described. Further application of paper cement will depend on the amount of use of the drafting board apparatus previously described herein and the ability of work-gripping surface 16 to hold work sheets 20 laterally smooth.

Again referring to FIG. 1 suitable sub-recesses 18 adjacent the sides of recess 12 of drawing board 10 facilitate the removal of work sheets 20 from the drafting apparatus recess 12 during process of patent preparation drawings. With such an arrangement of a recessed drawing board as shown in FIGS. 1 and 2 and described in the foregoing, the outer margin 17 serves as the pedestal support for a drafting blade 50 (shown in FIG. 8) placed across the recess 12 at any angle necessary to process a drawing while applying design delineating materials. The periphery of the drawing board apparatus as disclosed in FIGS. 1 and 2 may be circular as well as rectilinear as will be described hereinafter.

A modification of the embodiment illustrated in FIGS. 1 and 2 is graphically presented in FIGS. 3 and 4, wherein the elements 10' and 10" of FIG. 2 take the respective forms illustrated at 60' and 60" in FIG. 3 and are supplemented with a cover element 60''' hinged thereto as indicated at 61, the said cover 60''' being equipped with a cross blade 50 embodying the principle of bridging cut-out portion 64 of said cover 60''', the outer extremities of blade 50 being supported on pedestal outer margin surfaces 17' when cover 60''' is closed down on element 60', and screw pedestal 51 of said blade 50 engages lateral surface of work sheet 20, this principle of the invention being further shown in FIG. 8.

The assembly 60 shown in FIG. 3 has a base element 60' shaped out of a single piece of transparent material such as Lucite $\frac{1}{8}$ " thick x 10" wide x 21" long, a recessed and sub recessed frame element 60" fastened or cemented in place on top of element 60' and a cover element 60''' hinged at 61 by adhesive tape, the cover being made of a $\frac{1}{16}$ " thick x 10" wide x 20" long piece of Lucite or similar transparent material. Work-gripping pad 11 is then cemented in place at bottom of recess 12' of frame element 60" thereby completing this structural embodiment of the invention.

Comparing FIG. 3 with FIG. 2 it will be noted that this drawing board arrangement 60 includes a drawing board base 60' that is comparable to base 10' of FIG. 2, rectilinear frame 60" having recess 12' to accommodate work-gripping pad 11, the latter being likewise comparable to upper frame 10" having recess 12 to enclose work-gripping pad 11. In both arrangements the gripping pad is securely fastened to bases 10' and 60' of drawing boards 10 and 60, and both arrangements thus allow the principle depicted in FIG. 8 to be practiced by having blade 50 bridged across recesses 12 and 12' and supported by pedestals 17 at the blade's outer extremities. In both cases the work sheet 20 may be placed on or removed as desired, with slots 18 facilitating easy removal of said work sheets 20.

Still referring to FIG. 3, a cover 60''' hinged by means of an adhesive tape 61 and a locating pin 62 fitting in holes 63 of pedestal 17 of frame 60" when cover 60''' is closed down upon said pedestal 17, has an opening 64 which is designed to allow only the usable section of work sheet 20 to be used while processing graphic illustrations.

Another feature of the embodiment shown in FIG. 3 is the simple but effective means to rotate the complete drafting board arrangement 60 with cover 60''' closed and located is by use of pivotal pin 65 and indexing pin 66 passing through holes 67 and 68 respectively of base 60' into a drafting table or suitable indexing plate placed on a drafting table (not shown).

Still another feature of the drafting board assembly as

depicted in FIG. 3, the base 10' and cover 60''' are both made of transparent material such as Lucite, making the device usable due to its portability, over a light box commonly known to the art, in tracing or designing patent illustrations.

Another embodiment is depicted in FIGS. 5 and 6, wherein the elements 10' and 10" of FIG. 2 take the forms illustrated at 70' and 70" in FIG. 5, wherein element 70", although in the form of a removable tray, nevertheless rests on the base 70', so that regardless of necessary dimensional alterations in contour, the said tray serves the function of the equivalent structure of FIG. 2. The outer margin surfaces 17 on the top of tray 70", like element 60" of FIG. 3 and frame element 10" of FIG. 2 may be fabricated by modern plastic molding techniques, and affords pedestal support for blade 50 with screw pedestal 51 bearing on the lateral top surface of work sheet 20. Thus there is again used the invention principle (see FIG. 8) in that the FIGS. 5-6 construction facilitates practice of the invention to the same degree as do board assemblies 10 of FIG. 2 and 60 of FIG. 3.

It will be noted that the assembly of FIGS. 5 and 6 differs from that of FIGS. 1 and 2 in that the central portion is apertured completely through the thickness of base 10' to permit penetration of light rays from any suitable source of illumination (not shown) located below the assembly, to be projected through base 10', transparent tray 70" and work-gripping pad unit 11. In many drafting operations, as for example, tracing and reproductive tasks, the use of under-surface lighting is helpful as a means of silhouetting and sharpening the images to be traced, reproduced, or re-designed. The exemplary dimensions suggested above for the structures of FIGS. 1 and 2 can advantageously be employed, with variations as dictated by circumstances, in the structure of FIGS. 5 and 6. The same is true as to contour of the structure, that is, the use of a circular contour in lieu of a rectangular contour, whenever rotary flexibility is desired.

FIG. 7 shows a modification of the invention wherein base element 70' is constructed of a solid piece of suitable material having a recess and sub-recesses formed, depressed or removed for the reception of tray 70", or for the work-gripping assembly 11 in the event said tray is not used.

Base element 70' need not be made of wood or plywood, but may be plastic molded, or the product of a modern die stamping material processing shop, where sheet metal is progressively formed, trimmed and reformed into various shapes and sizes as required.

The pedestal principle of having screw element 51 adjustable in blade 50 holding down work sheet 20 whereas surface pedestals 17 hold blade 50 laterally up above work sheet 20 is clearly represented by forces P₁, P₂ and P₃, respectively.

Referring to FIG. 8 and also to FIG. 30 of co-pending application 645, 652, a rotary type modification of the invention is shown, wherein a circularly contoured base 80' is pivotally mounted onto a conventional drafting board or table 81 by means of pivot-pin 82 and turnable 60 within a neat fitting circular cut-out 83 in a stationary drafting board cover 84.

Recess 12''' in base 80' may be any desired shape to suit type of work being processed, circular, rectangular or irregular, and houses a similar shaped work-gripping pad 11' having thereon a work sheet 20' adhered to said pad 11' ready for the application of delineating fluids.

Blade 50 supplied with finger pedestal 51 and bridged over recess 12''' and flexible on end pedestal surfaces 17 shows the invention principle already explained herein and further indicated by forces P₁, P₂ and P₃.

FIG. 9 is an enlarged and exaggerated illustration of how base 60' of FIG. 3 may be used when recessed portion 60" and cover 60''' are removed and only the main element 60' having work-gripping pad 11 affixed thereto remains.

Blade 50 having center pedestal 51, and outer extremities pedestals 52 and 53 adjusted approximately to desired depth 85 above work sheet 20, again shows how the blade 50 is elevated above the work surface of work sheet 20 during processing and at all times except for the contact points of the pedestals just referred to. Blade 50 is transportable laterally and indexable above the graphic work sheet 20, as well as in some modification described herein base 60' is also turnable such as shown in FIG. 8.

Arrows P₁, P₂ and P₃ in FIGS. 7, 8 and 9 indicate directions of force application, as explained in my earlier-filed patent application above-identified.

FIG. 9a shows a bristol board 13 having a coating of a white rubber based adhesive cement 15 applied to the undersurface, and three successive coatings 16 of said cement to the upper surface. This assembly is then cemented in place on any suitable base as for example, a properly dimensioned recessed area in the supporting frame such as illustrated in FIGS. 1-8, inclusive. Bristol board 13 of pad assembly 11 may be replaced by any other suitable materials such as press board, plastic or wood that the cement will adhere to effectively. The number of coatings do not necessarily have to be one under and three on top, as long as the desired adhesion to the base on the under side is accomplished and the desired adhesiveness on surface 16 is sufficient to hold work sheets to said surface 16 of assemblies 11 and 11'.

The screw pedestals are retractable and removable and are used in combination with the work-gripping pad only on those occasions when conditions require, as for example, when humidity is prevalent to the point where there is considerable difficulty in maintaining the work sheet flat against its supporting surface.

What I claim is:

Apparatus for use in executing graphic compositions, said apparatus comprising a frame having opposed peripheral surfaces in one plane and a depressed work-receiving central surface in a second plane parallel with, and below, said first plane, a pen-supporting blade spanning said opposed peripheral surfaces, pedestal means extending downward from said blade to engage the surface of the work-sheet over-lying said central surface, and recessed means integral with said frame for facilitating removal of the work-sheet from said central surface without disturbing the frame, said depressed central surface being constituted by a pad or mat adapted to hold the work-sheet by adhesive inter-engagement of the interfacial surfaces of said pad and work-sheet.
